UNITED STATES PATENT OFFICE.

LOUIS E. SADLER, OF ATTLEBORO, MASSACHUSETTS, ASSIGNOR TO F. H. SADLER & COMPANY, OF SAME PLACE.

DESIGN FOR A JEWEL-TRAY.

SPECIFICATION forming part of Design No. 34,984, dated August 20, 1901.

Application filed July 19, 1901. Serial No. 68,987. Term of patent 7 years.

To all whom it may concern:

Be it known that I, LOUIS E. SADLER, a citizen of the United States, residing at Attleboro, in the county of Bristol and State of Massachusetts, have invented and produced a new and original Design for a Jewel-Tray, of which the following is a specification, reference being had to the accompanying drawings, forming part thereof.

Figure 1 is a perspective view of a jewel-tray, showing my new design. Fig. 2 is a sectional view of the same.

As shown in the drawings, the leading or material feature of my design consists of the longitudinally-curved bed, subdivided into rectangular spaces by longitudinal and transverse grooves inclosed in a rectangular raised border extending above the curved surface of the bed at the ends, while the center of the

bed extends above the central portion of the ²⁰ raised border. The raised border extends from a base wider and longer than the aforesaid raised border, a marginal surface extending around the said raised border.

In the drawings, *a* indicates the base, *b* ²⁵ the raised border, and *c* the curved bed.

Having described my invention, what I claim as new, and desire to secure by Letters Patent, is—

The design for a jewel-tray, as herein shown ³⁰ and described.

In testimony whereof I have signed my name to this specification in the presence of two subscribing witnesses.

LOUIS E. SADLER.
